UNITED STATES PATENT OFFICE.

EMMA ROBERTON, OF NEW YORK, N. Y.

DESIGN FOR A BOTTLE.

No. 38,483.

Specification for Design.

Patented March 19, 1907.

Application filed January 28, 1907. Serial No. 354,588. Term of patent 7 years.

To all whom it may concern:

Be it known that I, EMMA ROBERTON, a citizen of the United States, and a resident of New York city, borough of Manhattan, State of New York, have invented a new, original, and ornamental Design for Bottles, of which the following is a specification, reference being had to the accompanying drawings, forming part hereof, wherein—showing my new design; and Fig. 2 is a side view thereof at right angles to Fig. 1.

I claim—

The ornamental design for a bottle, as shown.

EMMA ROBERTON.
